(57) **CLAIM**

The ornamental design for a ride on toy, as shown and described.

DESCRIPTION

FIG. 1 is a perspective view of a ride on toy showing our new design;

FIG. 2 is a front elevational view thereof;

FIG. 3 is a top plan view thereof; and,

FIG. 4 is a side elevational view thereof.

The surface or portions of the article not shown in the drawing or described in the specification form no part of the claimed design.
